UNITED STATES PATENT OFFICE.

MAMIE C. BARBERO, OF MAQUON, ILLINOIS.

DESIGN FOR A BADGE.

SPECIFICATION forming part of Design No. 21,585, dated May 31, 1892.

Application filed December 7, 1891. Serial No. 414,339. Term of patent 3½ years.

To all whom it may concern:

Be it known that I, MAMIE C. BARBERO, a citizen of the United States, residing at Maquon, in the county of Knox and State of Illinois, have invented and produced a new and original Design for Badges, of which the following is a specification, reference being had to the accompanying drawing, forming a part thereof.

10 The figure is a front elevation of my design, this view being deemed sufficient to fully illustrate my design.

This design is intended for badges, and the essential features thereof are shown in the accompanying drawing, which represents a plan view of the same. The harp is formed with 15 the side pieces curved outward at their middle portions and curved inwardly near their

extremities and with their extremities curved outward into a scroll and with two bars connecting the side pieces, one near the top and the other near the bottom, and with twisted wires representing the strings of the harp attached to the cross-pieces and perpendicular with the side pieces and formed with a scroll-shaped plate across its middle portion and with depending bangles, as shown in accompanying drawing.

I claim—

20 The design for a badge or pin, as herein shown and described.

MAMIE C. BARBERO.

Witnesses:

JOSIE TEFFT,
R. N. McCORMICK.
